REFRIGERATED COMMODITY BOX

John T. Fritsche, Bay Village, Ohio

Application November 10, 1949, Serial No. 126,547

4 Claims. (Cl. 62—116)

1

This invention relates to a commodity box such as is mounted in the wall of a house or building and has its interior accessible from both the inside and outside thereof so that various delivered commodities can be placed in the box from without the house or building and removed therefrom from within the house or building.

More particularly the invention relates to a refrigerated commodity box.

When perishable commodities such as dairy products and meats, for example, are delivered to a home and placed in the usual commodity box for receiving the same it frequently happens that such commodities may remain in the box a considerable length of time as, for instance, if the occupants of the house are not at home or if they do not promptly remove the commodities from the box. The commodities remaining in the box for a considerable period of time may result in the spoiling or deterioration of the same, particularly if it is hot weather.

An object of the invention is to provide an improved and novel commodity box of the type referred to and wherein perishable commodities can be safely placed and may remain for extended periods of time without danger of the same spoiling or deteriorating.

A further object is to provide a commodity box, particularly as referred to in the last object, and which box is so constructed that it may be adjusted to fit and be positioned in walls of different thicknesses, wherefore the boxes may be formed as a standard unit and need not be made in various sizes to interfit different wall thicknesses.

Further and additional objects and advantages not hereinbefore referred to will become apparent hereinafter during the detailed description of an embodiment of the invention which is to follow.

Referring to the drawings,

Fig. 1 is a front elevational view of a commodity box embodying the invention and shows the box mounted in a wall, the view being taken from the outside of the building.

Fig. 2 is a view similar to Fig. 1 but is taken from the inside of the building, while the refrigerating unit mounted in the box is indicated by dash lines.

Fig. 3 is a horizontal sectional view taken substantially on line 3—3 of Fig. 2 looking in the direction of the arrows, and

Fig. 4 is a sectional view corresponding to a portion of Fig. 3 and is on a larger scale than Fig. 3.

2

The commodity box embodying the invention and illustrated in the drawings comprises an outside plate or member or end wall 10 which may be formed of wood, metal or any other suitable material. The plate or member 10 is positioned over an opening through a wall indicated generally at 11 and extends beyond the edges of the opening and is secured to the outer wall 12 by suitable securing means as, for instance, the bolts illustrated.

The outer plate or member or end wall 10 in its lower portion is provided with a rectangular opening that is normally closed by a door 13. The door 13 is shown as hinged to the plate 10 along one of the vertical edges of the door by suitable hinges 14 which may be spring hinges. The other vertical edge of the door 13 mounts a lock or latch 15, the bolt of which cooperates with a keeper 16 carried by the plate 10 to secure the door in closed position.

The door 13 is formed of two sheets, one of which is planar and constitutes the outer surface of the door while the second sheet is secured to the inner side of the first sheet and has an inwardly extending portion 17 spaced from the first sheet and adapted when the door is closed to interfit the opening in the wall similarly to the construction of refrigerator doors. Suitable insulation 18 may be positioned in the space defined between the outer sheet and the portion 17 of the inner sheet of the door 13.

The outer plate 10 is provided with a rectangular groove surrounding the opening closed by the door 13 and this groove mounts a suitable thermal insulating gasket 19 engaged by the door when the latter is closed. The plate 10 has secured to its inner side so as to extend into the building opening bottom, top and side walls 20. These bottom, top and side walls preferably are formed of spaced parallel wall elements between which suitable insulation 21 may be positioned.

The opening through the building wall has mounted over its inner end a plate or member or end wall 22 secured to the inner wall 23 of the building wall by suitable means as, for instance, the bolts illustrated. The plate 22 is provided with a lower opening closed by a lower inside door 24 and an upper and preferably smaller opening closed by an upper inside door 25.

The lower inside door 24 is constructed similarly to the outer door 13 and is secured to the inner plate 22 by the hinges 26 and mounts a latch or lock 27, the bolt of which cooperates with a keeper 28 secured to the plate 22. The upper door 25 may be similarly constructed and is hinged to the inner plate 22 by

the hinges 29 and likewise carries a latch or lock 30, the bolt of which cooperates with a keeper 31 secured to the inner plate 22. Bottom, top and side walls 32 similar to the walls 20 previously referred to are secured to the inner side of the plate 22 and telescope within the walls 20 as clearly shown in Fig. 3. The telescoping arrangement just referred to enables the commodity box to be adjusted to fit walls of various thicknesses and hence the box can be standardized as distinguished from the necessity of making it in various sizes.

An insulating gasket 33 is interposed between the walls 20 and the walls 32 for a purpose which is obvious. Secured to the inner plate 22 and to the inner sides of the walls 32 intermediate the upper and lower openings in the plate 22 is a horizontally extending partition 34 which separates the commodity box and particularly the inner section thereof into upper and lower compartments. If desired, the outer section of the commodity box can be provided with a similar partition located as to overlap the underside of the partition 34.

The partition 34 mounts a mechanical refrigerating unit indicated in Fig. 2 generally at 35 and which may be of conventional form and include the usual motor and compressor. Pipes extend from the compressor through the partition 34 to the refrigerating coil 36 carried by the underside of the partition 34 and located in the lower compartment.

Suitable circuit breakers in the electrical circuit to the motor of the refrigerating unit may be operatively associated with the outer door 13 and the inner door 24 to effect deenergization of the motor in case either of these doors is left open and to automatically close the circuit to the motor when the doors are closed. Also, suitable spring means may be operatively associated with the doors 13 and 24 to maintain the same normally closed as, for instance, the hinges 14 and 26 may take the form of spring hinges.

It will be understood that the door 25 provides access from the inside of the building to the upper compartment wherein the refrigerating unit is located.

From the foregoing it will be evident that a delivery man may open the door 13 from the outside of the building and place in the lower compartment of the box whatever commodities he is delivering. In case the commodities include perishable ones, such as dairy products or meats, they may remain in the box without danger of spoiling or deteriorating for an indefinite time inasmuch as the temperature within the box will be maintained sufficiently low to properly refrigerate the commodities. Of course the occupant of the house can remove the commodities in the usual way by opening the door 24 from the inside of the house to obtain access to the lower compartment of the commodity box. If desired the box may be used as an auxiliary or overflow refrigerator should the necessity occur.

Although a preferred embodiment of the invention has been illustrated and described herein, it will be understood that the invention is susceptible of various modifications and adaptations within the scope of the appended claims.

Having thus described my invention, I claim:

1. A commodity box of the character described comprising a container formed of two telescopically adjustable sections, each section including bottom, side and top walls and an end wall; the bottom, side and top walls of one sec-

tion telescoping within the corresponding walls of the other section; thermal insulating means interposed between the telescoping walls of said sections, the end wall of one section being adapted to be secured to the inner side of the building or house wall and the end wall of the other section being adapted to be secured to the outer side thereof, said end walls being provided with openings affording access to the interior of the container, and doors mounted on said end walls for normally closing said openings.

2. A commodity box as defined in claim 1 and wherein one of said sections includes interiorly thereof a supporting shelf, a mechanical refrigerating unit mounted upon said shelf and including a refrigerating coil for refrigerating the interior of the container.

3. A commodity box as defined in claim 1 and wherein the bottom, side and top walls of each section are secured to the end wall of the respective section and are formed of spaced parallel wall elements having thermal insulating material located between said elements, while said doors each includes an outer planular door element having secured thereto an inner door element provided with a portion offset from said outer door element and interfitting the end wall opening, thermal insulating material being interposed between said outer door element and said offset portion of the inner door element.

4. A commodity box of the character described comprising a container adapted to be mounted in a through opening in the outside wall of a building or house and including bottom, top, side and end walls, said end walls being adapted to be positioned over the opposite ends of said building or house wall through opening and of a size larger than the opposite ends of said opening so as to overlap and be secured to the opposite sides of said outside building or house wall to form in effect part thereof; said bottom, top and side walls being adapted to be located within said through opening in the outside building or house wall, a support located interiorly of said container intermediate the bottom and top walls thereof and dividing said container into upper and lower compartments with one of said compartments extending uninterruptedly between said end walls, said bottom, top and side walls being connected to said end walls while said support is connected to said side walls, said end walls being provided with openings communicating with said one compartment, doors mounted on said end walls for closing said openings therein, a mechanical refrigerating unit mounted on said support with the refrigerating coil thereof located within said one compartment while the remainder of said unit is located within the other of said two compartments, said side, bottom and top walls of said container and said doors comprising spaced parallel wall elements having thermal insulating material mounted therebetween.
